WALL MOUNTED DESK AND TELEPHONE SHELF COMBINATION

Carl Smittkamp, Vinton, Iowa

Filed July 11, 1963, Ser. No. 75,742

Term of patent 7 years

(Cl. D33—7)

FIG. 1

FIG. 2

FIG. 3

FIG. 4

The side not shown is like the side shown.

I claim:

The ornamental design for a wall mounted desk and telephone shelf combination, as shown and described.
